G. H. KUHL

AUTOMATIC TELEPHONE SYSTEM

Original Filed May 8, 1919

UNITED STATES PATENT OFFICE.

GEORGE H. KUHL, OF CHICAGO, ILLINOIS, ASSIGNOR TO AUTOMATIC ELECTRIC COMPANY, OF CHICAGO, ILLINOIS, A CORPORATION OF ILLINOIS.

AUTOMATIC TELEPHONE SYSTEM.

Application filed May 8, 1919, Serial No. 295,535. Renewed October 6, 1923.

To all whom it may concern:

Be it known that I, GEORGE H. KUHL, a citizen of the United States of America, and a resident of Chicago, in the county of Cook and State of Illinois, have invented certain new and useful Improvements in Automatic Telephone Systems, of which the following is a specification.

My invention relates in general to an automatic telephone system and more specifically to an improved non-numerical line switch of the rotary type for use in such a system.

Among the objects of my invention are to provide a line switch which is driven by gears in such a manner as to render its operation comparatively silent and also to reduce the wear and tear due to the operation of a ratchet and pawl such as is usually used in the rotary type of line switch. By the use of a motor such as I have shown, and which is disclosed and claimed in a prior application of John Erickson, Serial No. 259,062, filed October 21, 1918, I have provided such a gear driven line switch which is efficient and speedy in its operation as well as silent and which has a longer life than the usual type of line switch.

Further objects are to provide certain novel and improved circuit details and arrangements which tend to provide a practical and useful line switch of its type.

Further details and improvements will be pointed out hereinafter.

I will now describe the operation of the line switch more in detail, reference being had to the accompanying drawings in which:

Fig. 1 shows a calling line A of the automatic type provided with the usual talking equipment and a calling device, a line switch C which embodies the feature of my invention, and a selector switch D of the well known Strowger type which is accessible to the line switch C. The selector D may have access in the usual manner to additional similar selectors and connector switches for completing connections, or to connector switches direct without departing in any way from the spirit of my invention, as it will be seen that such a line switch C may be used with any type of line or switches either

in a full automatic system or in a semi-automatic system as a traffic distributor.

Fig. 2 shows the mechanism of the motor magnet of the line switch C with its devices for rotating the wiper shaft to advance the wipers of the switch.

Fig. 3 shows an alternative means for controlling the motor magnet of the line switch C.

Figure 4 shows a sectional view of the motor magnet along the line A in Figure 2.

When the receiver at substation A is removed to initiate a call a circuit is completed for the line relay 2 of the line switch C in series with the line A and to the ground G. Relay 2 energizes to close a series circuit from ground through springs 3, relay 4, and magnet 5 of the motor magnet to battery. At the same time a circuit is closed from private wiper 7, through springs 8 and 9, springs 10, and through magnet 5 to battery. Now it will be seen that should the trunk upon whose contacts the wipers of the switch C are standing be busy at this time there will be a ground present on the test contact 11 of that trunk which will complete a short circuit of the relay 4 and complete the last traced direct circuit for the magnet 5. The motor of the line switch C as shown in Fig. 2 is of a type shown in said application of John Erickson having a rotary armature which is alternately influenced by a pair of magnets thereby causing the armature to rotate in always the same direction, a worm gear is attached to an extension of the armature and is associated with a gear wheel which is firmly fixed to the wiper shaft to drive the same in one direction continuously over the contacts in the bank. The wipers are of the double ended type, one end of the wipers being always in engagement with a set of the contacts in the bank. The energization of the magnet 5 over the above traced circuit causes the armature of the magnet to be moved one half turn and therefore to step the wipers of the switch off the contacts on which they are standing and to a mid-point between sets of contacts. The wiper 13 is off set on the shaft so that it is always one half step behind the other wipers 12, 7 and 14, so that it is out of engagement with the contacts of

its bank while the other wipers are in engagement with their respective contacts. Now, as explained, when magnet 5 energizes the wipers 12, 7 and 14 move one half step 5 out of engagement with the contacts of the busy trunk line and the wiper 13 moves into engagement with a contact such as 15 which is permanently grounded. A circuit is at this time completed for the other operating 10 magnet 6 of the motor magnet to cause the armature to complete its full rotation. This latter half step of the armature moves the wipers 12, 7 and 14 into engagement with the contacts of the next trunk line and 15 moves the wiper 13 out of contact with contact 15.

This alternate operation of magnets 5 and 6 will again be accomplished in the same manner if the next trunk line is busy. However, 20 if the next line is idle then there will be no ground present on contact 11, to which it will be assumed the wipers have advanced. In this case there will be no short circuit completed about the relay 4 and relay 4 will 25 therefore energize in the before traced series circuit with magnet 5. Relay 4 being of comparatively high resistance does not permit the energization of the magnet 5. Relay 4, upon energizing, removes the ground 30 and relay 2 from the line circuit and extends the line of substation A through to the wipers 12 and 14 which are assumed to be in connection with the selector D. A circuit is completed in the usual manner for the line 35 relay 16 of the selector D which closes the circuit of slow relay 17 which in turn operates to prepare a circuit for vertical magnet 18 and slow relay 19 and also to supply holding ground to the release trunk to maintain 40 the relay 4 of line switch C energized. Relay 16 is then controlled by the calling device to operate the vertical magnet 18 to step the wipers to a level of the bank, after which 45 relays 19 and 20 co-operate in the usual manner to control the rotary magnet 21 to step the wipers automatically to an idle trunk line. Relay 22 energizes as soon as 50 such idle trunk line is reached to switch the connection through to the wipers of the switch D and thence to the selected trunk line which may, as stated, lead either to other automatic switches or to an operator's trunk circuit.

The release of the apparatus shown is 55 controlled in the usual manner by the restoration of the receiver at the calling phone which causes the removal of ground from the release trunk and the consequent deenergization of the relay 4 of the line switch C. 60 This deenergization of relay 4 restores the line switch C to normal condition in readiness for a succeeding call. It will be seen therefore that this line switch is driven always in one direction by the operation of a 65 motor magnet which consists of two mag-

nets, one controlled directly over the private wiper and the other controlled over a special wiper two impulses to the magnet causing one step of the wipers.

In the modification which I have shown 70 in Fig. 3 I have shown simply a different means for controlling the magnet of the switch C which will render unnecessary the use of an extra wiper 13 and its set of contacts in the bank. In this modification I 75 have shown only a portion of the switch C as it will be understood that the only change necessary will be the circuit of the motor magnet and that the relays 2 and 4 will function the same as before. Referring to 80 Fig. 3 when the relay 2' energizes the circuit will lead from the private wiper through springs 10', springs 30 and 31, and magnet 5' to battery. In this instance the gears controlled by the motor magnet will be changed 85 in ratio so that one half turn of the armature of the motor magnet will move the wipers one whole step from one set of contacts to the next, so that when the above circuit of magnet 5' is closed said magnet operates to step the wipers of the switch to the next set of contacts and also operates to open the springs 30 and 31 and close springs 30 and 32. The closure of springs 30 and 32 90 will not occur until the wipers are in engagement with the next trunk line and if this next trunk line is busy then the operation of magnet 6' causes another full step of the wipers and brings them into engagement with the next trunk line. Magnet 5' in the 95 meanwhile falls back and again prepares a circuit for itself. This operation of the two magnets alternately from successive trunk lines continues until an idle trunk is reached at which time relay 4' energizes to open the 100 circuit of the motor magnet from the private wiper and to open the springs 33 and 34 and close the springs 34 and 35. This operation has no effect at this time as relay 2' maintains the springs 36 open for an interval 105 after its circuit is opened. In releasing, however, after a call is finished when the relay 4' deenergizes, a circuit is momentarily completed for the magnet 6' from ground through springs 33, 34 and 35, springs 36, 110 and said magnet to battery. This is simply to insure that the armature stands in readiness to be moved in the next succeeding call as magnet 5' is energized. It being understood that if magnet 5' were energized last 115 in the preceding call, then deenergized without operating 6', then in the next call the magnet 5' being energized to step the wipers would have no effect on the rotary armature.

It will be seen therefore, that I have provided a very simple and speedy line switch of the gear driven type for accomplishing the objects pointed out and which has a 120 novel method of control.

Having fully described and ascertained the features and aspects of my invention, what I consider to be new and desire to have protected by Letters Patent will be pointed out in the appended claims.

What I claim as my invention is:

1. In a telephone system, a line, a non-numerical switch for said line, wipers for said switch, a pair of magnets each operating to move the wipers, means for energizing one of said magnets over one of said wipers to move said wipers to complete a circuit for the other magnet to extend a connection from said line, each magnet having a circuit including one of said wipers. 10
2. In a telephone system, a line, a non-numerical switch individual to said line, wipers for said switch, a pair of magnets, a circuit for each magnet including a wiper of the switch and means for closing said circuits alternately to move said wipers to extend a connection from said line. 20
3. In a telephone system, an automatic switch, a motor for driving said switch, a pair of wipers for the switch, said motor consisting of a pair of magnets having a common armature, and a circuit for each magnet including one of said wipers. 25
4. In a telephone system, an automatic switch, a motor for driving said switch, a pair of wipers for the switch, said motor consisting of a pair of magnets, and a circuit for each magnet including a wiper, and means for causing said magnets to be alternately energized over said wipers to move the wipers. 30
5. In a telephone system, a non-numerical automatic switch having movement in only one plane, a motor for driving said switch consisting of a pair of magnets, a circuit for each magnet, and means controlled by each magnet for automatically closing the circuit of the other magnet to operate said switch in a step by step manner to select an idle trunk. 40
6. In a telephone system, an automatic switch, a motor for driving the switch consisting of a pair of magnets, wipers for said switch, a circuit for each magnet including a wiper of the switch, said circuits closed alternately by said wipers to cause the motor to operate the automatic switch. 50
7. In a telephone system, an automatic switch, trunk lines accessible to said switch, a motor for driving said switch, a test contact for each trunk line, a normally grounded contact for each trunk line, wipers for the switch, certain of said wipers co-operating with said contacts, said motor controlled over said test contact and a wiper of the switch to move the wipers out of engagement with the trunk line associated therewith, and controlled over said grounded contact and a wiper of the switch to step the wipers of the switch into engagement with the next trunk line. 60
8. In a telephone system, an automatic switch, a motor for driving the switch, wipers for the switch, trunk lines accessible thereto, two successive operations of the motor being required to move the wipers of the switch one step from one trunk line to another, and means for giving the motor one of the successive operations required over a circuit including one wiper of the switch and another operation over a circuit including another wiper. 70
9. In a telephone system, a non-numerical line switch, a motor individual to said switch for driving said switch, said motor having a gear for directly operating the wipers of the switch in a step by step manner. 80
10. In a telephone system, a non-numerical line switch, wipers for said switch, a shaft carrying said wipers, a gear on said shaft, and a motor individual to said switch having a worm gear co-operating with the gear on the wiper shaft to drive the wipers in a step by step manner. 85
11. In a telephone system, a non-numerical line switch, wipers for said switch, a shaft carrying said wipers, a gear on said shaft, and a motor individual to said switch having a worm gear co-operating with the gear on the wiper shaft to drive the wipers always in one direction in a step by step manner. 90
12. In a telephone system, a non-numerical line switch, wipers for said switch, a shaft carrying said wipers, a gear on said shaft, and a motor individual to said switch having a worm gear co-operating with the gear on the wiper shaft to drive the wipers in a step-by-step manner. 100
13. In a telephone system, a subscriber's line, an automatic switch individual to said line responsive to the closure of said line to automatically select an idle trunk line, wipers for the switch, a motor individual to said switch, and co-operating gears driven by said motor to operate the switch to perform its selecting operation by advancing said wipers. 105
14. In a telephone system, a subscriber's line, an automatic switch individual to said line responsive to the closure of said line to automatically select an idle trunk line, a motor for said switch, and co-operating gears driven by said motor to operate the switch to perform its selecting operation, said motor consisting of a pair of magnets operated alternately over the wipers of the switch. 110
15. In a telephone system, a subscriber's line, an automatic switch individual to said line responsive to the initial closure of said line to automatically select an idle trunk 120

- 4
- line, a motor for said switch, a private wiper for said switch, said motor individual to said switch controlled over said wiper to move the switch solely by means of gears.
16. In a telephone system, a non-numerical automatic switch for extending connections, a motor individual to said switch for operating said switch, said motor having a pair of fields and a common armature, each field having a separate circuit controlled by the armature for automatically controlling said armature to select an idle trunk.
17. In a telephone system, an automatic switch, wipers for the switch, contacts accessible to the wipers, a motor for driving the wipers, a pair of field coils for the motor, an armature for the motor, said wipers acting as brushes over a commutator consisting of the contacts and directly in the circuit 20 of the field coils to move the armature of the motor.
18. In a telephone system, an automatic switch, wipers for the switch, contacts accessible to the wipers, a motor for driving the wipers, a pair of field coils for the motor, an armature for the motor, said wipers acting as brushes over a commutator consisting of the contacts to alternately control the field coils to move the armature of 30 the motor, said wipers directly in the circuit of said field coils.
19. In a telephone system, a step-by-step automatic switch having wipers and contacts, a pair of magnets having a common armature for rotating said wipers, said magnets each controlled over a separate wiper of the switch to step said wipers over their contacts.
20. In a telephone system, an automatic switch, contacts accessible thereto, wipers cooperating with said contacts, a motor for driving said wipers having a pair of magnets each connected to one of said wipers, means for maintaining one of said wipers normally in engagement with the test contact of a trunk line, one magnet operated over said test contact to move said wiper out of engagement with said test contact and to complete a circuit for the other magnet including the other wiper and one of its contacts, said other magnet energized over this completed circuit to step the wipers into engagement with a contact of the next trunk line.
21. In a telephone system, an automatic switch, trunk lines accessible thereto having test contacts, wipers for the switch cooperating with said test contacts, a motor for driving said wipers having a pair of magnets controlling a common armature, each magnet having a circuit including a separate wiper of the switch, and means for completing the circuit of said magnets alternately over said wipers to step said wipers from the contacts of one trunk line to the next.
22. In a telephone system, a non-numerical switch, a wiper set for said switch including a test wiper, bank contact sets adapted to be engaged by said wiper set, two motor magnets for stepping said wiper set, a circuit including said test wiper for energizing one of said motor magnets to step said wiper set, a circuit for energizing the other of said motor magnets to step said wiper set, 75 and means for closing said circuits alternately.
23. In a telephone system, a non-numerical switch, a wiper set for said switch including a test wiper, sets of bank contacts adapted to be engaged by said wiper set, two motor magnets for stepping said wiper set, and means for energizing said motor magnets alternately over said test wiper to advance 80 said wiper set over said bank contact sets.
24. In a telephone system, a non-numerical switch, a wiper set for said switch including a test wiper, bank contact sets adapted to be engaged by said wiper set, two motor magnets for stepping said wiper set, a circuit for energizing one of said motor magnets including said test wiper and a bank contact in one of said contact sets to step 90 said wiper set, and a circuit including said test wiper and a bank contact in another of said sets for energizing the other of said motor magnets to again step said wiper set.
25. In a telephone system, a non-numerical switch, a wiper set for said switch including a test wiper, bank contact sets adapted to be engaged by said wiper set, two motor magnets for said switch, a circuit for one of said motor magnets including said test wiper, a circuit for the other of said motor magnets including said test wiper and controlled by 100 the first magnet, and means for energizing said magnets alternately to advance said wipers.

Signed by me at Chicago, Cook County, Illinois, this 5th day of May, 1919.

GEORGE H. KUHL.
